Shephard Whitman 9784X
Petitioner Patent

The Schedule referred to in these Petitioners Patent and making
part of the same containing a description in the words of the said
Shephard Whitman himself of his improvement in the Ro-
tary Steam Engine.

To all persons to whom these presents shall come,
Shephard Whitman in the County of Elkhart and State of Indiana
and Town of New Albion, Physician and Engineer sends
(Greeting). Be it known that I the said Shephard Whit-
man have after patient and investigation and at great expense
invented and put to use a new and useful improvement in the
mode of working steam to produce mechanical power, called
Whitman's Rotary Steam Engine, which is described in the
following words to wit: It consists of a cast iron wheel twenty
eight inches diameter and when finished is an inch thick hav-
ing on its circumference a rim or flange projecting over one side like
the flange of a cast iron boiler head or like the cover of a snuff box
to the distance of one inch, and one each except on the inside of
this rim are cast teeth, the section of which are triangular
and are somewhat like the teeth of a rag or rathet-wheel, only
the teeth are on the inside, these teeth or buckets are $5\frac{1}{2}$ of an
inch deep and $\frac{1}{2}$ of an inch broad on their base and one inch long,
they stand about $6\frac{1}{2}$ inches apart and in all called the spaces
between the bases of the teeth should be equal to the bases of the
teeth themselves. These teeth are enclosed by the plate or
disk of the wheel on one side, and on the other side by a circu-
lar plate, about $5\frac{1}{2}$ inches broad and 28 inches diameter
screwed tight to the rim of the main wheel. This wheel
^{is upon a shaft} hangs on a shaft 30 inches long and the body of the shaft
is about one and $\frac{1}{2}$ or may be two inches diameter,
the journals are $\frac{1}{4}$ of an inch diameter and five inches long,
this

This shaft may be made of steel or iron but steel is the best. The journals run on leather, but for longer ones good bell metal is thought to be preferable. There is a central stationary wheel, secured in its proper place by fastening to the cast iron log which envelopes the whole. This central stationary wheel is of such diameter that when placed between the disks of the main wheel and the flat cover or ring that the bottom of the groove which is made around the whole circumference of this stationary wheel, which is one inch wide, $\frac{3}{8}$ of an inch deep, will approach the inner points of the buckets to the distance of $\frac{3}{4}$ of an inch. This central stationary wheel, has attached to it at the upper side a conductor or conveyor of the steam which directs the steam in the form of the teeth or buckets, directing the steam in a line as near at right angles with the radius of the wheel as may be. The mouth of the conductor should be the groove of the stationary central wheel, the open part of which at the discharging point is one inch long, $\frac{3}{16}$ wide. The case which envelopes the engine may be made square or round as best suits the form of the building, but if made square room may be left at the bottom to heat the supply water. The steam escapes immediately behind the conductor by an opening made further from you through the central stationary wheel and is discharged on to the case or envelope through a circular opening around the other shaft, and thence to the gun air through an opening of proper size at any convenient place. On this shaft toward one end is placed a collar or other metal fitting 5 inches diameter and 6 inches long. This fitting carries a leather belt over the surface of a wheel some 5 or 6 feet diameter thus retarding the motion until its useful purpose is wanted. The motion of this engine will be when the steam is at one hundred pounds to the superficial square inch about six thousand revolutions per minute when at work but when not

now, without any load. Its motion would be something like that of 10 or 11 thousand per minute. The opening of ^{one} drift, furnish of a square inch will discharge as much steam at 100 pounds against force as 15 feet of boiler fire surface will make under ordinary circumstances. The engine I have just described having an opening of $\frac{1}{16}$ of an inch would require 12×15 fire surface, 180° and would require two cylinder boiler 28 inches diameter and 36 feet long. This would produce about a 30 horse power or a power of 460 pounds moving at the rate of 1080 feet per minute. The proportions of this engine may be varied to infinity, but the one here laid down is at this time the best for a 30 horse power engine. But notice the power increases to 100, or thousand horse power the diameter of the wheel should be increased etc. But it is the mounted council of opinion that the diameter of the wheel in the case ought to exceed five feet. Hand or belt will not all tend to be used unless the motion exceeds that of a mill stone. To reduce the motion of the engine here described making 6000 revolutions - the pulley on the shaft being 5 inches. A drum 6 feet diameter would reduce it to 4160 revolutions and this motion can be easily reduced further to suit any purpose whatever by other bands and pulleys. It should be remarked that the gear should always be so as to give the engine not less than five thousand revolutions when the wheel is 28 inches diameter or you cannot obtain the power of the steam or in other words the motion of the engine forward of the wheel should never be less than one half of the motion of the steam you are working. See 100th The motion is about 1800 feet per second. or 100,000 feet per minute for as the one half that or 50,000. A further description of the engine is deemed superfluous and the reader is referred to an approximation of the model at the patent office made on a scale of $\frac{1}{6}$ of an inch to an inch in all its essential parts. The peculiar ground on which

372.

as patient is claimed as the following, and that the steam is
perfected in the inside of the boiler in such a manner as
to prevent its communication and escape before it has regulated
its influence to move the whole. - The parts of the engine
where the steam is applied in this packing, never meet each
other, either at top or bottom, of such a size, that the steam
is compelled to pass from the cavity of the first cylinder
to that of the second, and escape in hollow shafts, & that
from top, and in such a manner as to pass much more power
than any other engine, which can be kept in a given time, and
in the top of the cylinder, as in the description of
my last patent. I have made and may have this
engine of different sizes, and of various kinds, the standard
size of cylinder being 12 inches diameter, and 18 inches
stroke, and the engine being 1000 pounds weight.
